(57) **CLAIM**

The ornamental design for a handle, as shown and described.

DESCRIPTION

FIG. 1 is an isometric view of a handle showing our new design in a non-illuminated state.

FIG. 2 is a front elevation view thereof.

FIG. 3 rear elevation view thereof.

FIG. 4 right side elevation view thereof.

FIG. 5 is a left side elevation view thereof.

FIG. 6 is a top plan view thereof.

FIG. 8 is an isometric view a handle showing our new design in an illuminated state.

FIG. 9 is a front elevation view thereof.

FIG. 10 rear elevation view thereof.

FIG. 11 right side elevation view thereof.

FIG. 12 is a left side elevation view thereof.

FIG. 13 is a top plan view thereof; and,

FIG. 14 is a bottom plan view thereof.

The portions of FIGS. 1–14 shown in broken dash lines form no part of the claimed invention and are for illustrative purposes only. Neither the portions of the invention shown in broken dash line nor the broken dash lines themselves form any part of the claimed invention. The portions of FIGS. 8–12 shown in stippled diffusion dither represent the design as shown in an illuminated state.

1 Claim, 8 Drawing Sheets
